UNITED STATES PATENT OFFICE.

JOHN A. MARKOE, OF WHITE BEAR, MINNESOTA.

ENVELOP-SEALING MACHINE.

No. 820,427.

Specification of Letters Patent.

Patented May 15, 1906.

Application filed April 1, 1905. Serial No. 253,266.

To all whom it may concern:

Be it known that I, JOHN A. MARKOE, a citizen of the United States, residing at White Bear, in the county of Ramsey and State of Minnesota, have invented certain new and useful Improvements in Envelop-Sealing Machines; and I do hereby declare the following to be a full, clear, and exact description of the invention, such as will enable others skilled in the art to which it appertains to make and use the same.

My invention relates to envelop-sealing machines, and has for its object to improve the same in view of simplicity and efficiency.

To these ends the invention consists of the novel devices and combinations of devices hereinafter described, and defined in the claims.

In the accompanying drawings, which illustrate my invention, like characters indicate like parts throughout the several views.

Figure 1 is a plan view of the improved machine. Fig. 2 is a side elevation of the same, some parts being broken away; and Fig. 3 is a vertical section taken through the machine on the line $x^3 x^3$ of Fig. 1.

The numeral 1 indicates a bed-plate, upon which is rigidly secured a laterally-spaced pair of upright frame-plates or brackets 2, 30 that are rigidly tied together, as shown, by four tie-rods 3, 4, 5, and 6. The envelops are delivered over an inclined deck, made up of a plurality of inclined rods 7, that are tied together at their ends by thin plates 8 and 9. 35 Working over the lower ends of this inclined feed-deck is a plurality of rubber-faced feed-wheels 10, carried by a shaft 11, journaled in and projecting through the bearing-plates 2. This shaft 11 is provided at one end with a 40 sprocket 12 and at its other end with a gear 13. The feed-wheels 10 work in vertical planes midway between the rods of the inclined deck. Above the wheels 10 is a water-trough 14, which is attached at its ends to the bearing-plates 2.

The numeral 15 indicates a water-supplying tank, which, as shown, is detachably rested on the tie-rod 5 and on one edge of the water-trough and is provided with a depending 50 discharge-neck 16, which when turned into the trough automatically maintains the level of the water in the trough. This water-tank 15 when removed and turned upside down may be filled with water introduced through 55 its neck 16.

Working in the trough 14 and projecting

into the water thereof is a moistening-roller 17, preferably of rubber. The shaft of this roller 17 is journaled in the bearing-plates 2 and is provided at one end with a sprocket 60 18, over which and the sprocket 12 of the feed-shaft 11 runs a sprocket-chain 19. Working in frictional contact with the primary moistening-roller 17 is a secondary moistening-roller 20, the shaft of which is 65 preferably mounted in bearing-boxes 21, that are adjustably seated in the bearing-plates 2 and are subject to thrust-screws 22, by means of which the two rollers 17 and 20 may be pressed together under any desired tension. 70

Mounted to slide on the rods 7 of the inclined feed-deck under the action of gravity is a follower-head made up of an inclined plate 23, end brackets 24, and tie-bars 25, which tie-bars are notched at their under 75 edges to fit the upper portions of said rods 7.

The envelops 2 are arranged in a pack with their flaps and bodies in angular arrangement, as shown in Fig. 3, and their body portions are inserted between the follower-plate 23 80 and the adjacent side of the water-trough 14. The mucilaged surfaces of the flaps of the envelops will be subjected in succession to the secondary moistening-roller 20 and will be moistened to the desired extent. Said secondary roller, it will be noted, always engages with the flap of the innermost envelop, the lower edge of the body portion of which is in engagement with the feed-wheels 10. Under rotation of the feed-wheels 10 the one envelop 90 after the other will be carried from the stack over the lower ends of the inclined rods 7 of the feed-deck, and the follower-head under the action of gravity will move downward, so as to always maintain the envelops in a 95 closely-pressed pack.

The envelops fed from the pack by the feed-wheels 10 will be delivered onto one member 26 of a pair of sealing-rollers 26 27. The axes of the shafts of the two rollers 26 and 27 100 lie approximately in the plane of the inclined feed-deck made up of the rods 7. The shaft of the roller 26 is journaled in the bearing-plates 2, and at one end is provided with an operating-lever 28, and at its other end with a spur-gear 29, which latter meshes with the spur-gear 13 of the feed-shaft 11. The shaft of the roller 27 is journaled in bearing-boxes 30, that are slidably mounted in the bearing-plates 2 and are subject to springs 31 on said 110 side plates, which springs yieldingly press the roller 27 toward the roller 26. From a

broad point of view the several feed-wheels 10 constitute a feed-roller, although for an important purpose such feed-roller is sectioned. The envelops fed by the feed-wheels 10 onto the roller 26 are thrown against an inclined deflecting-plate 32, which, as shown, is supported at its lower edge by the tie-rod 3 and at its upper edge has lugs 33, secured to the bearing-plates 2 by screws or other suitable devices. To limit the upward movement of the envelops, the deflecting-plate 32 is provided with a stop-plate 34, that projects inward over the upper edge thereof. This stop-plate 34 is made adjustable, so that it may be set the proper distance from the roller 26 to permit the envelop to be moved laterally into alignment with a passage between the two rollers 26 and 27. As shown, this adjustment is accomplished by screws 35, that work through slots 36 in the downturned web of said stop-plate 34 and are screwed into the deflecting-plate 32. By reference to Fig. 3 it will be noted that the envelops in passing from the feed-wheels 10 against the deflecting-plate 32 and from thence through the space between the rollers 26 and 27 are reversed—that is, turned with their flap edges downward, as indicated by dotted lines in Fig. 3—so that in passing between the said rollers the moistened flaps are tightly pressed to the bodies of the envelops and the envelops thus sealed. The sealed envelops are by the rollers 26 and 27 dropped onto the bed-plate 1 or are discharged at any suitable point. As shown, they are caused to accumulate in a stack between guide-posts 37, fixed on the bed-plate, and a bracket 38, loosely rested on said bed-plate.

40 The machine described has been constructed and put into actual use and has been found to be extremely efficient for the purposes had in view. Furthermore, the machine is extremely simple, is of small cost, and has no parts that are liable to get out of order.

From what has been said it will be understood that the machine described is capable of modification within the scope of my invention, as herein set forth and claimed.

50 What I claim, and desire to secure by Letters Patent of the United States, is as follows:

1. The combination with a feed-roller and a moistening device located the latter over the former, of a follower movable transversely of said feed-roller and moistening device to deliver the bodies of the envelops to said feed-roller and the open flaps thereof to said moistening device, and a sealing device receiving the moistened envelops from said feed-roller, substantially as described.
2. The combination with an inclined feed-deck and a follower movable thereon for feeding the envelops, of a feed-roll overlying said feed-deck and serving to feed, one after an-

other, the envelops delivered thereto by said follower, a moistening-roller overlying and extending parallel to said feed-roller in position to engage the open flaps of the envelops as they are fed by said feed-roller, and a sealing device receiving the moistened envelops from said feed-roller, substantially as described.

3. The combination with an inclined feed-deck, and a follower mounted to move thereon for feeding envelops, of a feed-roller overlying a portion of said feed-deck and serving to feed, one after another, the envelop delivered thereto by said follower, of a pair of sealing-rollers arranged to feed the envelops transversely of the plane of said feed-deck, and a deflecting-plate positioned to engage the envelops as they are delivered from said feed device, and to reverse and deliver the same to said sealing-rollers, substantially as described.

4. The combination with an inclined feed-deck for envelops made up of a plurality of inclined rods, a follower mounted to slide on said rods, under the action of gravity, a water-trough above said feed-deck, a moistening device working in said trough and operative on the flaps of the envelops, a sectional feed-roller made up of a plurality of wheels, said wheels working in vertical planes between the lower ends of the rods of said feed-deck, a pair of sealing-rollers having their axes substantially in the plane of said feed-deck, and a deflecting-plate standing in position to engage the envelops delivered from said feed-roller, and to reverse and deliver the same between said sealing-rollers, substantially as described.

5. The combination with an inclined feed-deck for envelops made up of inclined guide-rods 7, of a follower-head detachably and slidably mounted on said guide-rods and having an inclined plate 23, a water-trough secured above said feed-deck, a roller water-distributer working in said trough and adapted to act upon the flap of the envelops, a plurality of rubber-faced feed-wheels 10 constituting a sectional feed-roller, and working in planes intermediate of said guide-rods 7, the sealing-rollers 26 27, having their axes in approximately the plane of said feed-deck, a fixed deflecting-plate 32 extending above said roller 27, a stop-plate 34 adjustably secured to the upper portion of said deflecting-plate, and means for driving all of the rollers noted from a common source, substantially as described.

In testimony whereof I affix my signature in presence of two witnesses.

JOHN A. MARKOE.
